US00D729357S

(12) **United States Design Patent**
Ball et al.

(10) **Patent No.:** **US D729,357 S**
(45) **Date of Patent:** **** May 12, 2015**

(54) **DRAIN ELBOW**

- (71) Applicant: **WCM Industries, Inc.**, Colorado Springs, CO (US)
- (72) Inventors: **William T. Ball**, Colorado Springs, CO (US); **Eric Pilarczyk**, Colorado Springs, CO (US)
- (73) Assignee: **WCM Industries, Inc.**, Colorado Springs, CO (US)
- (**) Term: **14 Years**
- (21) Appl. No.: **29/484,008**
- (22) Filed: **Mar. 5, 2014**

Related U.S. Application Data

- (63) Continuation of application No. 13/974,690, filed on Aug. 23, 2013, which is a continuation-in-part of application No. 13/726,840, filed on Dec. 26, 2012, which is a continuation-in-part of application No. 13/461,422, filed on May 1, 2012, now Pat. No. 8,505,132, which is a continuation-in-part of application No. 12/057,660, filed on Mar. 28, 2008, now Pat. No. 8,166,584, which is a continuation-in-part of application No. 10/732,726, filed on Dec. 10, 2003, now Pat. No. 8,302,220, which is a continuation-in-part of application No. 09/954,420, filed on Sep. 17, 2001, now Pat. No. 6,691,411.
